CLAIM

The ornamental design for a top divider for a golf bag, as shown.

DESCRIPTION

FIG. 1 is a perspective view,
FIG. 2 is a top view,
FIG. 3 is a front view,
FIG. 4 is a right-side view,
FIG. 5 is a rear view,
FIG. 6 is a left-side view,
FIG. 7 is a bottom view,
FIG. 8 is a cross section view taken along line 8—8 of FIG. 2; and,
FIG. 9 is a perspective view thereof, wherein the broken line portions of the disclosure are for illustrative purposes only and form no part of the claimed design.
